Primary Examiner — Steven J Czyz*Assistant Examiner* — Hillary Catherine Shepard(57) **CLAIM**

I claim the ornamental design for a foldable desk, as shown and described.

DESCRIPTION

FIG. 1 is a perspective view of a foldable desk, showing my new design;

FIG. 2 is a front view thereof;

FIG. 3 is a bottom view thereof;

FIG. 4 is a top view thereof;

FIG. 5 is a rear side view thereof;

FIG. 6 is a left side view thereof; and,

FIG. 7 is a view in folded position thereof.

The broken line portion of the figure drawings is included to show portions of the article that forms no part of the claimed design.

1 Claim, 7 Drawing Sheets(56)
